UNITED STATES PATENT OFFICE.

MARIO COSTA, OF EAST WALLINGFORD, CONNECTICUT.

RUBBER HEEL.

1,235,013.

Specification of Letters Patent. Patented July 31, 1917.

Application filed November 27, 1916. Serial No. 133,524.

To all whom it may concern:

Be it known that I, MARIO COSTA, a citizen of the United States, residing at East Wallingford, in the town of Wallingford, 5 county of New Haven, State of Connecticut, have invented new and useful Improvements in Rubber Heels, of which the following is a specification, reference being had therein to the accompanying drawings.

10 My invention relates to a new and improved rubber heel, having for its object, among other things, to provide a heel of resilient material that may be readily attached and detached from a shoe and de-

15 signed so that it may be used either on the right or left shoe.

To these, and other ends, my invention consists in the rubber heel, having certain details of construction and combinations of 20 parts, as will be hereinafter described and more particularly pointed out in the claims.

Referring to the drawings, in which like numerals of reference designate like parts in the several figures;

25 Figure 1 is a plan view, partly in section, of my improved heel;

Fig. 2 is a sectional view thereof, taken upon line 2—2 of Fig. 1, with a portion of the shoe attached;

30 Fig. 3 is a front elevation of the heel;

Fig. 4 is a plan view of the retaining plate; and

Fig. 5 is an end elevation thereof.

Referring to the drawings, the numeral 1 35 designates a portion of a shoe and 2 a retaining plate permanently connected therewith by means of the prongs 3, which project into the shoe and are clenched substantially as shown in Fig. 2. This retaining plate is preferably made of sheet metal 40 with a flange 4 upon its front end, in which is rotatably mounted the turn button 8. The surface 5 of this plate is so formed that its outer edge is in a lower horizontal plane 45 than the surface 6, which contacts with the underside of the shoe, so that when said plate is fastened to the shoe, as shown in Fig. 2, there is an open space 7 between the surface 5 and the underside of said shoe.

50 The heel is designated by the numeral 9 and is made of rubber or other resilient material, and embedded therein during the process of manufacture, is a lock plate 10, having an inwardly projecting flange 11 55 upon the top side thereof, of substantially

the same shape as the retaining plate 2, and so secured to said heel as to leave an open space 12 between the underside thereof and the surface 13.

The heel 9 is attached to the shoe with the 60 retaining plate 2 within the lock plate 10, at which time the flange 11 overhangs said retaining plate and lies within the open space 7 while the edge of the retaining plate 2 lies within the open space 12. When in 65 this position the heel is locked against movement by a hinge 14 pivotally secured to the lock plate 10 by the pintle 15 and having an opening 16 therein through which projects the head of the turn button 8.

To insure a positive and water-tight joint 70 between the heel 9 and shoe, the outer edges of the heel are beveled as at 17.

A heel constructed as herein shown and described is capable of being readily attached and detached by the ordinary person and without the aid or assistance of skilled labor, and when so attached is rigidly secured to the shoe.

By reason of the method of attachment 80 above described, the heel may be shifted from the right to the left shoe, and vice versa, thereby very materially increasing the length of time that said heel can be used.

Having described my invention, what I 85 claim as new and desire to secure by Letters Patent, is:

1. The combination with a shoe, of a retaining plate fixed thereto, having a projecting portion thereon around the outer edge 90 thereof in a plane distant from said shoe; a heel made of resilient material; a locking plate connected with said heel and having a portion thereon which engages with the projecting portion of said retaining plate; and 95 means for separably securing said plates together, comprising a hinge upon one of said plates, and a button upon the other of said plates, which engages said hinge when said plates are in engagement with each other. 100

2. The combination with a shoe, of a retaining plate fixed thereon; a heel of resilient material; a lock plate secured therein; a hinge connected with said lock plate; and a button connected with said retaining plate, which engages said hinge when said plates are in engagement with each other. 105

In testimony whereof I have hereunto affixed my signature.

MARIO COSTA.
